UNITED STATES PATENT OFFICE.

JOHN E. HILL, OF CENTER HARBOR, NEW HAMPSHIRE,

DESIGN FOR A COLLAR OR CUFF BUTTON.

SPECIFICATION forming part of Design No. 33,453, dated October 30, 1900.

Application filed October 3, 1900. Serial No. 31,937. Term of patent 7 years.

To all whom it may concern:

Be it known that I, JOHN E. HILL, a citizen of the United States, residing at Center Harbor, county of Belknap, State of New Hampshire, have invented and produced a new and original Design for a Collar or Cuff Button, of which the following is a specification, reference being had to the accompanying drawings, forming a part thereof.

Figure 1 is a perspective view of a collar or cuff button embodying my design, and Fig. 2 is a side elevation thereof.

The leading feature of my design for a collar or cuff button consists in an elongated slightly-convex head, having a flat shank projecting centrally therefrom and at right angles thereto, said shank terminating in a gooseneck, the free end of which curves inward slightly toward the head. As shown in

the drawings, the elongated head *a* is slightly convex, as at *b*, and has projecting therefrom, approximately centrally of its length, the flat shank *c*, the said shank terminating in the gooseneck *d*. The free end *e* of the gooseneck is bent inward slightly toward the head *b*, as at *f*.

Having described my invention, what I claim as new, and desire to secure by Letters Patent, is—

The design for a collar or cuff button as herein shown and described.

In testimony whereof I have signed my name to this specification in the presence of two subscribing witnesses.

JOHN E. HILL.

Witnesses:

HARRY H. BLACKY,
E. H. GOULD.
